UNITED STATES PATENT OFFICE.

GEORGE SIEGENTHALER, OF FREMONT, OHIO.

HAME ATTACHMENT.

No. 902,845.

Specification of Letters Patent.

Patented Nov. 3, 1908.

Application filed December 14, 1907. Serial No. 406,553.

To all whom it may concern:

Be it known that I, GEORGE SIEGENTHALER, a citizen of the United States, residing at Fremont, in the county of Sandusky and 5 State of Ohio, have invented certain new and useful Improvements in Hame Attachments, of which the following is a specification.

My invention relates to improvements in hame attachments, and has for its object the 10 provision of an interchangeable, adjustable, combined trace-holder and breast-strap holder.

The invention further consists in the novel 15 construction and arrangement of the hame-attachment, and its combination with the hame-bar, as hereinafter more fully described, illustrated in the drawing, and more hame-bar, as hereinafter more fully de-particularly pointed out in the claim here- 20 unto appended.

In the drawing: Figure 1 is a view in front elevation of a hame-bar, having one of my interchangeable, adjustable hame-attachments applied thereto. Fig. 2 is a side elevation of Fig. 1, and Fig. 3 is a sectional view of the attachment.

This invention is designed as an improvement on my invention for hame attachments for which Letters Patent of the United States 30 were granted to me October 6, 1896, No. 568,880. In that invention the hame attachments were designed to be made in "rights" and "lefts", that is, each pair of hames required a "right" hand attachment for the 35 right hand hame-bar, and a "left" hand attachment for the left hand hame-bar. In the present invention I have designed an attachment that may be used on either hame-bar, thus doing away with the necessity for two 40 distinct attachments for each pair of hames. This construction not only reduces the cost of manufacture of a pair of hames, but is also found to be exceedingly convenient and inexpensive in making repairs.

45 Referring to the drawing, the numeral 1 indicates a hame-bar, and 2 the usual metallic strip secured thereon. The hame-bar for which this attachment is designed has its draft-sustaining portion, that portion lying 50 between the lines $x-x$, $x-x$, being about

five inches of its length, of practically the same size.

The numeral 3 indicates my interchangeable, adjustable combined trace and breast-strap holder.

5 4 indicates the trace-loop or holder, and 5 the breast-strap ring-holding bracket. The numerals 7, 7, indicate bands for holding said trace-loop and breast-strap ring-holding bracket to the hame-bar. For the purpose of 60 strength and rigidity I prefer to have the bands, bracket and trace-loop made integral, but it is perfectly obvious that the same may be made separately and afterwards secured together in any suitable or convenient manner. The breast-strap ring-holding bracket 5 extends from band 7 to band 7, and is provided therein midway between the two bands with a suitable opening 8 into which is se-cured a breast-strap ring 8', as shown.

70 The numerals 9, 9, indicate screw-threaded openings in said attachment, one above and the other below the trace-loop, and 10, 10, suitable binding screws adapted to set in said screw threaded openings and secure 75 said attachment to the hame-bar. The ends of the binding screws 10, 10, are hollow or concaved for the purpose of affording a greater binding surface on the metallic strip 2 of the hame-bar. By reason of the draft-sustaining portion of the hame-bar being of uniform size the attachment 3 may be ad-justed to any portion thereof, as desired, and securely held thereto by means of the set 80 screws 10, 10, as is evident. It is also ob-85 vious that by reason of the arrangement and location of the breast-strap bracket and the ring secured therein, the attachment may be used on either hame-bar without making any 90 difference in the appearance of a pair of hames.

Having thus fully described my invention what I claim and desire to secure by Letters Patent of the United States, is—

95 In a pair of hames, the combination with a hame-bar having the draft-sustaining por-tion of its length of about the same size throughout, of an adjustable trace-loop and breast-strap bracket, and bands for holding said trace-loop and breast-strap bracket to 100

the hame-bar, said breast-strap bracket being integral with said bands and trace loop and so arranged and positioned that the center of its draft will be midway between
5 the two bands, and set screws for clamping said parts in any desired position on the draft-sustaining portion of the hame-bar.

In testimony whereof I affix my signature, in presence of two witnesses.

GEORGE SIEGENTHALER.
